UNITED STATES PATENT OFFICE.

RAIMONDO C. AIMONE, OF NEW ROCHELLE, NEW YORK, ASSIGNOR TO NEW JERSEY PATENT COMPANY, OF WEST ORANGE, NEW JERSEY, A CORPORATION OF NEW JERSEY.

DESIGN FOR A PHONOGRAPH-CABINET.

52,722.

Specification for Design.

Patented Dec. 10, 1918.

Application filed July 19, 1918. Serial No. 245,763. Term of patent 14 years.

To all whom it may concern:

Be it known that I, RAIMONDO C. AIMONE, a citizen of the United States, residing at New Rochelle, in the county of Westchester and State of New York, have invented a new, original, and ornamental Design for a Phonograph-Cabinet, of which the following is a specification, reference being had to the accompanying drawing, forming a part thereof.

The figure is a perspective view of a phonograph cabinet showing my new design.

I claim:

The ornamental design for a phonograph cabinet as shown.

RAIMONDO C. AIMONE.
